UNITED STATES PATENT OFFICE

131,498

DESIGN FOR A VISE

Hugh W. Vogl, Wilmette, Ill.

Application August 1, 1941, Serial No. 102,618

Term of patent 14 years

To all whom it may concern:

Be it known that I, Hugh W. Vogl, a citizen of the Republic of Czechoslovakia, and residing in Wilmette, in the county of Cook and State of Illinois, have invented a new, original, and ornamental Design for a Vise, of which the following is the specification, reference being had to the accompanying drawings, forming a part thereof.

Fig. 1 is a top plan view of a vise showing my new design.

Fig. 2 is a side elevational view thereof; and Fig. 3 is an end view looking from the right of Fig. 2.

I claim:

The ornamental design for a vise, substantially as shown.

HUGH W. VOGL.
